UNITED STATES PATENT OFFICE.

JAMES H. BAKER, OF SARATOGA SPRINGS, NEW YORK.

PULP SCREEN.

1,404,566.

Specification of Letters Patent. Patented Jan. 24, 1922.

Application filed November 15, 1919. Serial No. 338,165.

To all whom it may concern:

Be it known that I, JAMES H. BAKER, a citizen of the United States, residing at Saratoga Springs, in the county of Saratoga and State of New York, have invented an Improvement in Pulp Screens, of which the following is a specification.

This invention relates to a machine for screening wood pulp stock for the manufacture of paper. Heretofore various forms of pulp screens have been employed, and in some instances apparatus for screening paper pulp stock have included series of screens together with means for agitating the same. In other instances, the stock is conveyed to a screen drum or barrel and forced through the same by different forms of centrifugal devices, while in still other types of this form of apparatus, the pulp stock is conveyed to a receptacle containing a screen and is forced through the same by suitable diaphragms. The present invention relates to the latter type of apparatus and in carrying out the same, I employ a suitable vat or receptacle in which there is mounted a drum or screen barrel; I also employ series of circumferentially disposed diaphragms placed around the periphery of the screen drum, together with means for revolving the drum and simultaneously actuating the diaphragms to force the stock against the screen drum causing the finer portions thereof to pass through the slots or meshes of the drum to the interior thereof. The apparatus also includes means for admitting the stock to the vat or receptacle, means for conveying the screened stock from the apparatus, and also devices for clearing the surfaces of the screen drum from those portions of the stock which do not pass through the screen drum and conveying the same to a suitable place of deposit. Furthermore, in carrying out the invention, the diaphragms are each preferably provided with valves of suitable type to decrease the resistance of the same when moving from the screen drum while at the same time closing the valve openings when the diaphragms are moved toward the screen drum so that each diaphragm presents a continuous surface to force the pulp stock through the meshes of the screen drum, as will be hereinafter more particularly described.

In the drawing:

Fig. 1 is an end elevation and partial cross section of the pulp screen made in accordance with this invention.

Fig. 2 is a similar view taken from the opposite end of the apparatus.

Fig. 3 is a partial front elevation and cross section illustrating my improved pulp screen, and

Fig. 4 is a plan and partial cross section of the same.

Referring to the drawing, it will be seen that in carrying out this invention, the apparatus comprising the same includes a base 10, upon which in a suitable position bearing blocks 11 are mounted. In the bearing blocks 11, a shaft 12 is journaled, and on the shaft 12 a drive pulley 13 is suitably secured. On the base 10, there is also mounted a vat or receptacle comprising a trough member 14 to which the ends 15 of the vat are secured in any suitable manner. Within the receptacle there is mounted a screen drum or cylinder 16, the shaft of which is journaled in suitable bearings 17, and in the periphery of which there is suitably secured series of screen plates 18. These screen plates, as will be understood, may be made in any suitable manner with slots of required dimensions or of material of any suitable mesh to meet the requirements of the apparatus.

On the shaft 12, there is a beveled gear 19 meshing with a beveled gear 20 secured on a shaft 22, the shaft and the gears being enclosed in a suitable casing 21. On the shaft 22 there is a worm 23 meshing with a worm gear 24 on the shaft of the screen drum, and the worm and worm gear are inclosed in a suitable casing 25. As will now be understood, the screen drum is revolved from the pulley on the drive shaft 12 through the worm gear 24, the worm 23, the shaft 22 and the beveled gears 19 and 20.

On the drive shaft 12, I also employ an eccentric 26 fitted with an eccentric strap 27 to which is connected an eccentric rod 28. The head 29 of the eccentric rod is mounted on a screw spindle 30 suitably secured in a lever 31. This lever 31 at the lower end thereof is pivoted in a bracket provided therefor in the base of the apparatus as indicated at 32, and at its upper end the lever 31 is provided with a cap 33 through which the

screw spindle 30 passes and is swiveled so as to turn therein, and by turning to raise and lower the head 29 which is connected to the end of the eccentric rod so that in the operation 5 of the apparatus, the throw of this lever 31 as actuated by the eccentric rod may be adjusted as desired.

A rod 34 is pivotally connected at one end as indicated at 35 in a boss on the lever 31, 10 and at its opposite end, the rod 34 is pivotally connected as indicated at 36 to a link 37 mounted on a shaft 38 which is journaled in suitable bearings indicated at 39. On the other side of the lever 31, there is also a rod 15 40 which like the rod 34 is pivoted at one end as indicated at 41 in a boss provided therefor on the lever 31, while at its other end, the rod 40 is pivotally connected as indicated at 42 to a link 43 secured on a shaft 44 20 which is journaled in bearings indicated at 45. On the shaft 38 there are cams 37', and on the shaft 44 there are similar cams 43'.

A link 46 is pivotally connected at one end as indicated at 47 to a cam 43' and extends 25 through an opening provided therefor in the base of the apparatus, and at its opposite end is pivotally connected as indicated at 48 to one end of a lever 49. The opposite end of the lever 49 is pivotally connected 30 to a bracket 50 as indicated at 51, and approximately centrally thereof, the lever 49 is provided with a pivot pin 52.

On the exterior of the vat or receptacle, I employ 35 series of arms for actuating the diaphragms which are contained within the receptacle. In the drawing, I have illustrated a pair of arms at the front and also a pair of arms at the rear of the apparatus, but as will be understood, any desired number of 40 these arms may be employed as may be necessary, and as these arms and their connections with the diaphragms are the same, but one of them will be specifically described. One of these arms is indicated at 53. At its 45 upper end, the arm 53 is fitted with a link 54. The link 54 is pivotally connected to a bracket as indicated at 55 and is also pivotally connected to the upper end of the arms as indicated at 56. At the lower end 50 of the arm 53, the same is provided with an aperture 57 through which a rod or bolt 58 passes and around which exteriorly of the lower end of the arm there is a spring 59, the spring 59 extending between the outer 55 surface of the lower end of the arm and a handle 60 by which the tension of the spring may be adjusted, as will be readily understood, to maintain the lower end of the arm in contact with the face of the cam 43'. As 60 illustrated, the arm 53 is angular and at the angle thereof there is connected a diaphragm rod 61. At one end this diaphragm rod is connected in a yoke bracket which is pivotally connected to the angular portion of 65 the arm 53 as indicated at 62. The dia-

phragm rod 61 is journaled in a bearing 63 forming part of a bracket 64 which may be suitably connected by bolts or otherwise to the frame of the apparatus, with the diaphragm rod passing through the same. Connected to the diaphragm rod in any suitable manner, and also secured between the frame and the bracket 64, there is a yielding diaphragm 65 made of rubber or any other suitable material so as to make a tight joint and at the same time permit the diaphragm rod to reciprocate in order to actuate the diaphragm which is connected thereto. At the inner end of the diaphragm rod there is a head 66 secured thereto, and suitably connected to the head 66 is a diaphragm 67. The diaphragm 67 is made on the arc of a circle to conform to the periphery of the screen drum 16, and in suitable positions in the diaphragm 67 there are flap valves 68 connected thereto by rivets 69 or otherwise. These flap valves, as will be understood, normally cover the ports in the diaphragm when the diaphragms are moved toward the screen drum, but will permit the stock 90 contained in the vat or receptacle to pass through the openings in the diaphragm so as to relieve the pressure of the diaphragm in the movements of the same away from the screen drum. 95

One of the rods of the opposite side of the apparatus is indicated at 70, and this is connected to a diaphragm 71 placed in the position opposite the diaphragm 67, while in the lower part of the vat, there is a diaphragm 74 connected to a rod 73 which at its outer end is connected to a yoke 72 pivotally secured to the lever 49 by the pivot pin 52. 100

The apparatus is provided in a suitable position with an inlet 75 for the pulp stock to be screened and at the opposite side of the apparatus with a drain 76 which may be opened to draw out that part of the stock which does not pass through the screen drum and which is not cleared therefrom by the shower as hereinbefore described. The apparatus also includes a shower inlet 77 connecting with a suitable shower 78 placed interiorly of the screen drum, and also with a waste trough 79 connected with the sliver outlet 80 as well as with an outlet connection 81 for the screened stock. 110

In the operation of the apparatus, the screen drum is revolved as hereinbefore described, and as also hereinbefore described, the lever 31 is rocked through a predetermined angle by the eccentric rod 28. The lever 31 actuates the shafts 38 and 44 imparting thereto a rocking movement, which, by the cams 37' and 43' is imparted to the arms 53 on one side of the apparatus and the arms 70 on the other side of the apparatus respectively, these arms actuating the diaphragms 67 and 71, the lower frame 74 125

being actuated from the rocker shaft 38 by the link 46 and the lever 49, together with the connections between the lever 49 and this lower diaphragm as hereinbefore described.

- 5 Now as will be understood, when the diaphragms approach the screen drum, they force the stock through the recesses or meshes therein and in doing so, present a continuous surface to the stock, while in 10 moving in the opposite direction, the stock is permitted to pass through the ports in the diaphragms by means of the yielding flap valves employed. Also as the screen drum revolves, each section of the screen is cleared 15 or cleaned of the slivers or parts which do not pass through the screen by the shower and conveyed thereby to the waste trough 79 and thence to the sliver outlet 80 and to any suitable receptacle and the screened 20 stock passes from the interior of the screen drum by way of the outlet 81 to a place for use or to a suitable receptacle in which the same is stored.

I claim as my invention:

- 25 1. A pulp screen comprising a pulp stock receptacle, a screen therein, a diaphragm also within the receptacle and between the walls of the same and the said screen, a rod extending through the walls of the receptacle and upon which the said diaphragm is mounted, a yielding diaphragm making a tight joint for the rod, and means exterior of the receptacle for actuating the said rod to impart a reciprocating movement to the 35 said diaphragm.

2. A pulp screen comprising a base, a pulp stock receptacle, a screen therein, a diaphragm also within the receptacle and between the walls of the same and the said 40 screen, means for moving the diaphragm toward and away from the said screen, and devices in the diaphragm permitting the pulp stock to pass through ports therein when the diaphragm is moved away from 45 the screen.

3. A pulp screen comprising a base, a pulp stock receptacle, a screen therein, a diaphragm also within the receptacle and between the walls of the same and the said 50 screen, means for moving the diaphragm toward and away from the said screen, the said diaphragm having ports therein, and valves covering and closing said ports when the diaphragm is moved toward the screen 55 and opening to permit the pulp stock to pass through the said ports when the diaphragm is moved away from the screen.

4. A pulp screen comprising a base, a pulp stock receptacle, a screen therein, a diaphragm also within the receptacle between the walls thereof and the said screen, a swinging arm mounted and lying exteriorly of the receptacle, a rod connected to the swinging arm passing through the walls of 60 the receptacle and carrying the said dia- 65 phragm therein, and means for actuating the said swinging arm to reciprocate the dia- phragm, causing the same to move toward and away from the said screen.

5. A pulp screen comprising a base, a pulp stock receptacle, a screen therein, a dia- phragm also within the receptacle between the walls thereof and the said screen, a swinging arm mounted and lying exteriorly of the receptacle, a rod connected to the 75 swinging arm passing through the walls of the receptacle and carrying the said dia- phragm therein, means for actuating the said swinging arm to reciprocate the dia- phragm, causing the same to move toward 80 and away from the said screen, and means for varying the extent of motion given to the said swinging arm so as to vary the extent of the travel of the said diaphragm.

6. A pulp screen comprising a base, a pulp stock receptacle, a screen therein, a dia- phragm also within the receptacle between the walls thereof and the said screen, a swinging arm mounted and lying exteriorly of the receptacle, a rod connected to the 90 swinging arm passing through the walls of the receptacle and carrying the said dia- phragm therein, a lever mounted to rock on the said base, a cam for moving the said swinging arm, a link connecting the said lever and cam, and means for imparting a 95 swinging movement to the said lever.

7. A pulp screen comprising a base, a pulp stock receptacle, a screen therein, a dia- phragm also within the receptacle between 100 the walls thereof and the said screen, a swinging arm mounted and lying exteriorly of the receptacle, a rod connected to the swinging arm passing through the walls of the receptacle and carrying the said dia- 105 phragm therein, a lever mounted to rock on the said base, a cam for moving the said swinging arm, a link connecting the said lever and cam, means for imparting a swing- 110 ing movement to the said lever, and devices for varying the extent of the swinging movement imparted to the said lever.

8. A pulp screen comprising a base, a pulp stock receptacle, a screen therein, a plu- 115 rality of diaphragms also within the said receptacle and between the walls thereof and the said screen, swinging arms mounted and lying on the exterior of the receptacle, connections between the said swinging arms and the said diaphragms, and means for actuat- 120 ing the said swinging arms to impart a re- ciprocating motion to the said diaphragms to move the same toward and away from the said screen.

9. A pulp screen comprising a base, a pulp stock receptacle, a screen therein, a plu- 125 rality of diaphragms also within the said receptacle and between the walls thereof and the said screen, swinging arms mounted and lying on the exterior of the receptacle, con- 130

- nections between the said swinging arms and the said diaphragms, means for actuating the said swinging arms to impart a reciprocating motion to the said diaphragms to 5 move the same toward and away from the said screen, and devices for adjusting the extent of the movement of the swinging arms to vary the extent of the travel of the diaphragms.
10. A pulp screen comprising a base, a pulp stock receptacle, a screen therein, oppositely disposed diaphragms at the sides of the said screen and between the same and the walls of the receptacle, a diaphragm intermediate of the aforesaid diaphragms at the bottom of the receptacle and between the walls thereof and the said screen, and means for simultaneously actuating the said diaphragms to cause the same to move 15 toward and away from the said screen.
11. A pulp screen comprising a base, a pulp stock receptacle, a screen therein, oppositely disposed diaphragms at the sides of the said screen and between the same and the walls of the receptacle, a diaphragm intermediate of the aforesaid diaphragms at the bottom of the receptacle and between the walls thereof and the said screen, means for actuating the said oppositely disposed 20 diaphragms to move the same toward and away from the said screen, and devices actuating by the aforesaid means for operating the intermediate diaphragm to cause the same to move toward and away from 25 the said screen.
12. A pulp screen comprising a base, a pulp stock receptacle, a screen therein, oppositely disposed diaphragms at the sides of the said screen and between the same and the walls of the receptacle, a diaphragm intermediate of the aforesaid diaphragms at the bottom of the receptacle and between the walls thereof and the said screen, a series of arms mounted on the exterior of 30 the receptacle so as to swing thereon, connections between the said arms and the said oppositely disposed diaphragms, means for simultaneously actuating said arms to operate the said oppositely disposed diaphragms, 35 and devices actuated by the aforesaid means for operating the said intermediate diaphragm.
13. A pulp screen comprising a base, a pulp stock receptacle, a screen therein, oppositely disposed diaphragms at the sides of the said screen and between the same and the walls of the receptacle, a diaphragm intermediate of the aforesaid diaphragms at the bottom of the receptacle and between the walls thereof and the said screen, a series 40 of arms mounted on the exterior of the receptacle so as to swing thereon, connections between the said arms and the said oppositely disposed diaphragms, means for simultaneously actuating said arms to operate the said oppositely disposed diaphragms, 45 and devices actuated by the aforesaid means for operating the said intermediate diaphragm.
14. A pulp screen comprising a base, a pulp stock receptacle, a screen therein, oppositely disposed diaphragms at the sides of the said screen and between the same and the walls of the receptacle, a diaphragm intermediate of the aforesaid diaphragms at the bottom of the receptacle and between the walls thereof and the said screen, a series 50 of arms mounted on the exterior of the receptacle so as to swing thereon, connections between the said arms and the said oppositely disposed diaphragms, a rocking lever, means for actuating the same, cam members for operating the said arms, links connecting the said cam members with the said 55 rocking lever to actuate the said arms and thereby impart a reciprocating movement to the said oppositely disposed diaphragms, and means for operating the said intermediate diaphragm from one of the said cam members.
15. A pulp screen comprising a base, a pulp stock receptacle, a screen therein, oppositely disposed diaphragms at the sides of the said screen and between the same and the walls of the receptacle, a diaphragm intermediate of the aforesaid diaphragms at the bottom of the receptacle and between the walls thereof and the said screen, a series 60 of arms mounted on the exterior of the receptacle so as to swing thereon, connections between the said arms and the said oppositely disposed diaphragms, a rocking lever, means for actuating the same, cam members for operating the said arms, links connecting the said cam members with the said rocking lever to actuate the said arms and thereby impart a reciprocating movement to the said oppositely disposed diaphragms, a lever, a bracket in which the said lever is pivotally mounted at one end thereof, a link connecting the opposite end of the said lever with one of the said cam members, and a connection between the said lever and the said intermediate diaphragm for operating 65 the same from the said cam member.
16. A pulp screen comprising a base, a pulp stock receptacle, a screen therein, oppositely disposed diaphragms at the sides of the said screen and between the same and the walls of the receptacle, a diaphragm intermediate of the aforesaid diaphragms at the bottom of the receptacle and between the walls thereof and the said screen, a series 70 of arms mounted on the exterior of the receptacle so as to swing thereon, connections between the said arms and the said oppositely disposed diaphragms, a rocking lever, cam members for operating the said arms, links connecting the said cam members with the said rocking lever to actuate the said arms and thereby impart a reciprocating movement to the said oppositely disposed diaphragms, a lever, a bracket in which the said lever is pivotally mounted at one end thereof, a link connecting the opposite end of the said lever with one of the said cam members, and a connection between the said lever and the said intermediate diaphragm for operating 75 the same from the said cam member.

- the said rocking lever to actuate the said arms and thereby impart a reciprocating movement to the said oppositely disposed diaphragms, a lever, a bracket in which the 5 said lever is pivotally mounted at one end thereof, a link connecting the opposite end of the said lever with one of the said cam members, a connection between the said lever and the said intermediate diaphragm for 10 operating the same from the said cam member, and means for actuating said rocking lever and varying the travel thereof to correspondingly vary the extent of the travel of the said diaphragms.
- 15 17. A pulp screen comprising a base, a pulp stock receptacle, a screen therein, oppositely disposed diaphragms within the receptacle and between the same and the said screen, an intermediate diaphragm also 20 within the said receptacle and between the same and the said screen, swinging arms pivotally connected to the receptacle at the exterior thereof, connections between the said swinging arms and the said oppositely 25 disposed diaphragms, a drive shaft, a rocking lever, means for actuating the said rocking lever from the said drive shaft, cam members, links connecting the said cam members to the said rocking lever for operating the cam members to actuate the said 30 swinging arms and thereby impart a reciprocating movement to the said oppositely disposed diaphragms, a lever pivotally connected in the bracket secured to the said 35 base, a link connecting the said lever with one of the said cam members, and a connection between the said lever and the intermediate diaphragm whereby the said intermediate diaphragm is actuated from the 40 said cam member.
18. A pulp screen comprising a base, a pulp stock receptacle, a cylindrical screen member therein, means for turning the cylindrical screen member, oppositely disposed 45 diaphragms also in the receptacle and between the same and the said cylindrical screen, arms pivotally connected to the said receptacle at the exterior thereof, connections between the said arms and the said oppositely 50 disposed diaphragms, a drive shaft, a rocking lever, a screw spindle mounted in the said rocking lever, an eccentric on the said drive shaft, an eccentric rod connecting the said eccentric with a head adapted 55 to move on the said screw spindle in the said rocking lever, cam members, and links connecting the said cam members with the said rocking lever for actuating the said arms and the said diaphragms and varying 60 the extent of the movements thereof.
19. A pulp screen comprising a base, a pulp stock receptacle, a cylindrical screen member therein, means for turning the cylindrical screen member, oppositely disposed diaphragms also in the receptacle and 65 between the same and the said cylindrical screen, an intermediate diaphragm also within the said receptacle and between the walls thereof and the said screen, arms pivotally connected to the said receptacle at the exterior thereof, connections between the said arms and the said oppositely disposed diaphragms, a drive shaft, a rocking lever, a screw spindle mounted in the said rocking lever, an eccentric on the said drive shaft, 70 an eccentric rod connecting the said eccentric with a head adapted to move on the said screw spindle in the said rocking lever, cam members, links connecting the said rocking lever and the said cam members, a lever pivotally mounted at one end in a bracket, a link connecting the opposite end of the said lever with one of the said cam members, and a connection between the said lever and the said intermediate diaphragm whereby the 75 said diaphragms are moved toward and away from the said screen and the extent of the travel thereof may be varied.
20. A pulp screen comprising a base, a pulp stock receptacle, a screen therein, a diaphragm also within the said receptacle and between the same and the said screen, a rod upon which the said diaphragm is mounted, extending through the wall of the said receptacle, a bearing for the said rod, 80 a yielding diaphragm making a tight joint for the said rod, and means exterior of the receptacle for actuating the said rod to impart a reciprocating movement to the said diaphragm.
21. A pulp screen comprising a base, a pulp stock receptacle, a screen within the receptacle, a diaphragm also within the receptacle and between the walls thereof in the said screen, a bracket having a bearing 85 secured exteriorly of the receptacle, a rod journaled in the said bearing, passing through an opening in the walls of the receptacle and connected to the said diaphragm to support the same, a yielding dia- 90 phragm for making a tight joint at the place where the said rod passes through the opening in the wall of the receptacle, and means for actuating the said rod to impart a reciprocating motion thereto to move the said 95 diaphragm to and away from the said screen.

Signed by me this 31st day of October, 1919.

JAMES H. BAKER.
